UNITED STATES PATENT OFFICE.

JAMES D. ADAMS AND AUGUST G. JOHNSON, OF MONESSEN, PENNSYLVANIA, ASSIGNEES TO PITTSBURGH STEEL CO., OF PITTSBURGH, PENNSYLVANIA, A CORPORATION OF PENNSYLVANIA.

CORE FOR WIRE-REELS.

1,239,069.

Specification of Letters Patent.

Patented Sept. 4, 1917.

Application filed May 22, 1913. Serial No. 769,267.

To all whom it may concern:

Be it known that we, JAMES D. ADAMS and AUGUST G. JOHNSON, citizens of the United States, and residents of Monessen, in the county of Westmoreland and State of Pennsylvania, have invented a new and useful Improvement in Cores for Wire-Reels; and we do hereby declare the following to be a full, clear, and exact description thereof.

10 Our invention relates to cores or internal supports for wire-reels.

The object of our invention is to provide a core or internal support for reels formed of wire or other suitable material by means of which the reel is held from collapsing or bending under the strain of the winding of the wire upon the reel, and at the same time one which is quickly adjusted into position within the reel, and readily removed there-

20 from without sticking.

To these ends my invention comprises, generally stated, a base-piece, collapsible arms connected to said base-piece and to an outer supporting member, whereby when 25 said base-piece is seated on a fixed support the arms are distended, and when the core-member is removed, said arms move inwardly or collapse to permit of the ready withdrawal of the core-member from the reel.

30 Referring to the accompanying drawing Figure 1 is a perspective view of a reel to which our improved core is particularly adaptable; Fig. 2 is a sectional elevation of my improved core; Fig. 3 is a sectional view 35 showing the core in position within the reel and the reel mounted on the winding device; and Fig. 4 is a section on the line 4—4 Fig. 3.

In Fig. 1 of the drawing, we have illustrated a form of reel which has been made the subject of an application for Letters Patent of the United States filed by us, Serial No. 729,845. This reel consists of the end members 2 which are formed of a single 45 piece of wire bent in the form of a star with the radiating arms 3. The tie-members 4 connect the end-members 2, said tie-members having the loops 5 at each end thereof which are slipped over the arms 3 and engage the 50 seats or depressions 6 in said arms. When the reel is put together in this manner, it forms a reel in which the members are securely locked together, but in order to prevent the collapsing or bending of the tie-

members in reeling the wire thereon, it is 55 found desirable to employ a core-member or internal support during the winding operation. A base-piece or inner member 7 is provided with the square opening 8. Toggle-fingers 9 are pivoted to the lugs 10 on 60 the base-piece 7 and to the lower ends of the arms 11. The upper ends of the arms 11 are pivoted to the lugs 12 on the outer member 13. This outer member has the square opening 14 and is provided with the 65 grooves 15 and 16 to receive the looped ends of the tie-members 4 and the arms 3 of the end-members 2, respectively.

The member 7 is provided with the stops 17 with which the toggle-fingers 9 are 70 adapted to engage when the core-piece is seated in the reel and, furthermore, the fingers 9 have the nibs 18 which are adapted to engage the member 7 and control the movement of said toggle-fingers.

75 The core-member is inserted in the reel by passing it down through the open center of said reel and the operator grasping with his hands the outer member 13. When the inner member 7 strikes the floor or other 80 support, the weight above will tend to lower the arms 11 and the toggle-fingers 9 until said toggle fingers engage the stops 17, and the arms 11 move out into practically parallel position as indicated in Fig. 3. The reel 85 with the core inserted in it is then adjusted in the frame 19 of the twisting and winding device, said device having the member 20 corresponding to the outer member 13 and with which the inner member 7 contacts, while the grooves 21 receive the wires 90 of the end member and loops of the tie-member, as clearly shown in Fig. 3. The member 20 is connected to the bevel gear-wheel 22 by the screws 23. This bevel-gear 95 22 has the square opening 24 and the hub 25 which extends through the frame 19. The bevel-pinion 26 in the frame 19 meshes with the bevel gear-wheel 22. A square shaft 27 is then inserted in the square openings 100 14, 8 of the core-member, and the square opening 24 of the bevel gear-wheel 22. A yoke 27^a on the frame 19 is then brought in position to be held in place by the thumb-screw 28 to hold the shaft 27 in position. 105 When power is applied to rotate the pinion 26, the gear-wheel 22 is rotated and with it the reel and its core-member. The wire is

wound around the wheel in the ordinary manner and at the same time twisted and the pressure of the winding operation is sustained by the core-piece so that the reel is held from collapsing and bending due to the strain created by the winding operation. When the reel has been wound to its full capacity, the machine is stopped and the shaft 27 is removed which permits the reel 5 to be taken from the machine and the core-piece is then withdrawn. To accomplish this the member 13 is grasped and the reel and core jolted which will move the toggle-fingers 9 to the position shown in Fig. 2, 10 while at the same time the arms 11 will collapse and move inwardly, so as to free themselves whereupon the core may be readily withdrawn from the reel, which is then ready for shipment. The core-piece is then 15 ready to be inserted in another reel, when the above operation is repeated.

What we claim is:

1. A core-piece for reels comprising an inner member and an outer member, toggle-

fingers connected to said inner member, and 25 arms connected to said toggle-fingers and to said outer member.

2. A core-piece for reels comprising an inner member and an outer member, toggle-fingers connected to said inner member, 30 stops on said inner member in the path of said toggle-fingers, and arms connecting said toggle-fingers with said outer member.

3. A core-piece for reels, comprising an inner member and an outer member, toggle-fingers connected to said inner member having nibs at their inner ends, and arms connected at the outer ends of said toggle-fingers and to said outer member. 35

In testimony whereof, we the said JAMES 40 D. ADAMS and AUGUST G. JOHNSON have hereunto set out hands.

JAMES D. ADAMS.
AUGUST G. JOHNSON.
